NECKTIE PIN

Douglas E. Kirchner, Minneapolis, Minn., assignor to Kirchner's Kaynar Diamond Co., Minneapolis, Minn.

Filed Mar. 1, 1966, Ser. No. 1,223

Term of patent 14 years

(Cl. D45—19)

FIG. 1

FIG. 4

FIG. 2

FIG. 5

FIG. 3

FIG. 1 is a front elevational view of a necktie pin showing my new design;

FIG. 2 is a view in top plan thereof;

FIG. 3 is a rear elevational view thereof;

FIG. 4 is a side elevational view thereof as seen from right to left of FIG. 1, the side opposite that shown being substantially a mirror image; and

FIG. 5 is a view in bottom plan thereof.

I claim:

The ornamental design for a necktie pin, substantially as shown and described.
